MORTISE BUTT HINGE MARKER

Tyko K. Finneman, Portland, Oreg.

Application September 29, 1948, Serial No. 51,785

1 Claim. (Cl. 33—18)

1

This invention relates generally to carpenter's tools and particularly to a mortise butt hinge marker.

The main object of this invention is to provide an inexpensive and efficient butt hinge marker whereby the door and jamb may be accurately marked, preparatory to forming the hinge receiving portion.

The second object is to construct a tool of the class described which will be light in weight and which, by reason of its construction, can only mark the woodwork in an accurate manner.

These and other objects are accomplished in the manner set forth in the following specification as illustrated in the accompanying drawing, in which

Fig. 1 is a plan of the device.

Fig. 2 is a side elevation.

Fig. 3 is an end elevation.

Fig. 4 is a fragmentary view showing the mark left by the device on the door and jamb.

Fig. 5 is a section along the line 5—5 in Fig. 4.

Fig. 6 is a view taken along the line 6—6 in Fig. 5.

Like numbers of reference refer to the same or similar parts throughout the several views.

Referring in detail to the drawing, there is shown a common form of door 10 which is to be hinged to the jamb 11.

In order to make the door hang properly and the butt portions engage each other in proper alignment, it is necessary that the butt portions be accurately mounted on the door 10 and the jamb 11. In order to accomplish this purpose, I have provided a tool consisting of a cylindrical handle 12 in the end of which is placed a flat blade 13 having a chisel point 14 mounted in the slot 15.

Below the blade 13 and normal thereto is a vertical alignment blade 16 whose edge 17 is normal to the axis of the cylindrical handle 12. The end 18 of the blade 16 is somewhat below the bottom edge of the member 12.

2

The end 19 of the handle 12 is preferably chamfered as it is intended to be struck by a hammer 20.

The operation of the device is as follows: Assuming that the door 10 is properly positioned within its opening and the position of the hinges is determined, it is only necessary to insert the blade 16 into the crack 21 between the members 10 and 11, bringing the upper edge 22 of the chisel point 14 into register with the hinge location mark. The end 19 is struck with the hammer 20, leaving the two directly opposite chisel marks 23 and 24 in the members 10 and 11.

The ordinary try-square 25 is then used to mark the hinge boundaries by means of a knife or scribe (not shown). Obviously, this can be done for each hinge and at both ends of the hinge, providing an extremely accurate layout for the hinge cut-out.

20 The blade 16 is pressed into the lower portion of the slot 26 which, if convenient, extends across the body 12.

I claim:

25 A device of the class described, comprising a cylindrical handle having projecting from one end thereof a flat pointed chisel blade and also having projecting therefrom an alignment blade having one chisel edge projecting beyond the point of said pointed blade and having the outermost portion of said alignment blade extending laterally beyond the surface of said handle member and normal to said pointed blade.

TYKO K. FINNEMAN.
